(57) **CLAIM**

The ornamental design for a ceiling fan light fixture, as shown and described.

DESCRIPTION

FIG. 1 is a bottom perspective view of a ceiling fan light fixture showing my new design;

FIG. 2 is a left side elevational view thereof, the opposing right side elevational view being substantially the same thereof;

FIG. 3 is a bottom plan view thereof; and,
FIG. 4 is a top plan view thereof.

The broken lines in the views show environmental features, which are for illustrative purposes only and form no part of the claimed design.
